APPARATUS AND PROCESS FOR PRODUCING
ICE

Hans Tietz, Leverkusen-Wiesdorf, Germany, assignor to I. G. Farbenindustrie Aktiengesellschaft, Frankfort-on-the-Main, Germany

Application October 15, 1936, Serial No. 105,685
In Germany October 17, 1935

3 Claims. (CL 62—105)

This invention relates to the production of ice.

In an apparatus for producing ice by partial evaporation of water in vacuo it is difficult to introduce the water into the vacuum chamber. 5 On exit from the nozzles the water evaporates so suddenly that it splashes on to the walls of the apparatus, freezes and thereby clogs the apparatus, whereby a continuous working of the apparatus is made impossible, or ice forms at the 10 nozzle itself, so that the nozzle is finally completely clogged. To overcome these disadvantages many constructions, particularly heated nozzles, have been proposed.

In accordance with the present invention clogging of the nozzles by the ice formed is avoided 15 by introducing the water in a thin jet. This is obviously due to the fact that the capillary forces working against the evaporation are the higher the smaller is the diameter of the water jet. Now 20 it might have been expected that at a certain temperature at which the water is introduced the diameter of the jet would have to be chosen so that the sum of the surface tension of the jet and the absolute tension in the vacuum chamber 25 would at least be equal to the saturation pressure corresponding to the temperature of the water jet. However, it has been established that it suffices if the sum of the tensions is greater than the saturation pressure at 0° C. This is probably 30 due to the fact that the evaporation necessary for cooling the jet to 0° C. is so slight that it can be effected by mere evaporation at the surface without forming bubbles and splitting up of the jet caused thereby. That is to say the water jet must 35 be given a surface of so small a radius of curvature that the sum of the pressure in the apparatus and the surface tension of the water jet is greater than the saturation pressure of water at 0° C., that is greater than 40 4.58 mm. of mercury. Only if the saturation pressure at 0° C. exceeds the aforementioned sum of the tensions can the water jet cool by further evaporation below 0° C. and thereby freeze out as such. This, however, is the case only if 45 the jet falls upon a surface which destroys the jet as such and which spreads the water as a plane since in that case the surface tension suddenly ceases. The surface tension of a water 50 jet of a radius of 0.357 mm. is 1.58 mm. of mercury so that at a pressure of 3 mm. of mercury in the vacuum chamber the total pressure for rays of the radius indicated is equal to the pressure at the freezing point, that is to say each ray 55 of a smaller radius is protected against evapora-

tion and therewith freezing out at a pressure of 3 mm. of mercury.

My invention is further illustrated in the accompanying drawing in which:

Fig. I is a vertical section through an apparatus in which the present invention may be practiced and, 5

Fig. II is a detail view of the nozzle illustrated in Fig. I.

As shown in Fig. I, the apparatus may comprise 10 a vertical chamber 1 which is maintained under the desired vacuum by any suitable means. Within the vacuum chamber there is arranged an endless transport belt 2 which is provided with driving means (not illustrated). The bottom 15 3 of the vacuum chamber is made in the form of an inverted frustum of a cone in order to collect the pieces of ice formed. The ice accumulating at the bottom of the chamber 3 then passes to the screw conveyor 4 which forces the 20 ice out of the apparatus in the form of a continuous rope or rod. The ice is, of course, compacted at the exit point by means of the screw conveyor 4 thereby sealing the discharge opening of the vessel making it possible to maintain the vacuum 25 within the vessel without the use of any special valves. The water is supplied to the apparatus through the pipe 5 which terminates in a number of branch pipes 6. The pipes 6 are provided with a plurality of openings or nozzles 7 which 30 form water jets of such a small radius of curvature that the sum of the surface tension of the water jet and the absolute pressure in the vacuum chamber is greater than the saturation pressure of water at 0° C. For example if an absolute 35 pressure of 3 mm. of mercury is maintained in the vacuum chamber, the surface tension of the water jet must be at least equal to 1.58 mm. of mercury because the saturation pressure of water at 0° C. is 4.58 mm. of mercury. As indicated 40 above, a water jet of 0.357 mm. has a surface tension of 1.58 mm. of mercury. Accordingly if 3 mm. of mercury absolute are maintained in the chamber, each water jet must have a radius no larger than 0.357 mm. As shown the water jets are 45 impinged upon the endless belt 2 whereupon the jet is broken and the water spread out in the form of a film over the belt. Since the water in the form of a film has a lower surface tension than the jet, the sum of the surface tension of 50 the water film on the belt and the absolute pressure in the chamber falls below the saturation pressure of water at 0° C. whereupon evaporation takes place with consequent cooling and freezing.

In the above indicated manner the problem of 55

clogging of the nozzles used for introducing the water into an apparatus for producing ice has been solved in a very simple and convenient manner.

5 I claim:—

1. In an apparatus for producing ice by partial evaporation of water in vacuo, the combination of an evacuated chamber and a water introducing means therein giving to a water jet formed 10 in the apparatus so small a radius of curvature that the sum of the values of the pressure in the apparatus and of the surface tension of the water jet is greater than the value of the saturation pressure of the water at 0° C.
- 15 2. In a process for producing ice by partial evaporation of water in vacuo, the steps which comprise maintaining a low absolute pressure in a vacuum chamber, spraying water therein in a jet having so small a radius of curvature that 20 the sum of the values of the surface tension of

the water jet and the absolute pressure in the chamber is greater than the value of the saturation pressure of water at 0° C.

3. In a process for producing ice by partial evaporation of water in vacuo the steps which comprise maintaining a low absolute pressure in a vacuum chamber, spraying water therein in a jet having so small a radius of curvature that the sum of the values of the surface tension of the water jet and the absolute pressure in the vacuum chamber is greater than the value of the saturation pressure of water at 0° C. whereby evaporation of the jet is avoided and impinging the jet upon a surface to destroy the jet and to thereby reduce the aforesaid summation of values to a 15 value lower than the saturation pressure of water at 0° C. whereby evaporation of the water and simultaneous freezing thereof may occur.
